UNITED STATES PATENT OFFICE.

ALLEN W. MCKENZIE, OF HELENA, WISCONSIN.

CAR-COUPING.

SPECIFICATION forming part of Letters Patent No. 401,710, dated April 16, 1889.

Application filed April 16, 1888. Serial No. 270,883. (No model.)

To all whom it may concern:

Be it known that I, ALLEN W. MCKENZIE, a citizen of the United States, residing at Helena, in the county of Iowa and State of Wisconsin, have invented a new and useful Safety Railroad-Car Coupler, of which the following is a specification.

My invention relates to coupling railroad cars together with a link-coupling, or in a coupling where a link is used; and the objects of my invention are, first, to provide a means or device for coupling cars having a link-coupling without necessitating the brakemen or operators taking hold of and guiding the link with their hands; second, to afford facilities for properly adjusting and guiding the link, instead of taking hold of the same with the hand; third, to enable railroad employés to save time by making sure couplings; fourth, to enable the brakemen to couple cars having link-couplings without imperiling or being in the least possible danger of injuring or smashing their hands. I attain these objects by the mechanism illustrated in the accompanying drawings, in which—

Figure 1 is a view of the coupling device as it appears when attached to the draft-iron and swung up to a horizontal position by the operator when guiding the link; it hangs down at about right angles, or dotted line N, when not in use. Fig. 2 is the coupler as it appears when detached from attaching-strip and draft-iron. Fig. 3 is the attaching-strip having a bearing at one end for attaching to coupling device, Fig. 4 showing coupling device when made in one continuous piece, with the exception of the horizontal link-guiding cross-bar or handles K K; Fig. 5, a view of a swinging yoke for attaching coupling device to the wood-work or frame of the car. Figs. 2, 4, and 6 show three of the several different ways in which the safety-coupler may be made.

Similar letters refer to similar parts throughout the several views.

The safety-coupler A may be attached to draft-iron H by means of the metal strip B, which is bolted to the under side of said draft-iron, as shown in Fig. 1.

50 The safety-coupler A may be attached to

the wood-work or frame of any car by means of the yoke or swing C, (shown in Fig. 5,) and is so attached by passing the looped ends D D up from below, one each side of the draft-iron, and fastening them to the wood-work 55 of the car by means of eyelet-bolts or wood-screws.

The safety-coupler A, made as shown in Figs. 2 and 6, may be attached to yoke or swing C by bending the end E or ends E E 60 around said yoke, as shown in Fig. 5, the ends to be left loose enough to allow them to work like a hinge, which will give the safety-coupler A and yoke C a double-hinged action when attached to the car. The draft-irons on 65 all cars have a few inches play, or will move to and from the end of the car a short distance and will stay where left, and with the yoke or swing C attachment the operator is enabled to adjust the coupler A to the different 70 distances the end of the draft-iron may be from the end of the car. The coupler A hangs down in under the draft-iron H at about right angles with the lower side or bottom, similar to the dotted line N, when not in use. 75

The operator when using said coupler A takes hold of one of the handles K K and swings the coupler outward and upward until it comes in contact with and raises the coupling-link S to a sufficient height to enter it into an opposite 80 draft-iron. When the link enters an opposite or an approaching draft-iron, the coupling device A is forced down from between the draft-irons by the opposite one coming in contact with the slanting or sloping outward 85 end or part, R, and above the point F, said point being of a sufficient length to always project below the lowest part of an opposite draft-iron. When of a sufficient length it is impossible for the coupling device A to 90 get bent or broken by being caught between the draft-irons. When the operator is making a coupling, the horizontal link-guide, cross-bar, or handles K K is attached to the bent part of coupling device A on top or just under 95 the knees or elevated parts V V, or part V, as it appears in views Figs. 1, 2, 4, and 6, with bolts, rivets, or any suitable way.

The knees V V, just referred to, of coupling device A should be of sufficient height or 100

length to raise the coupling-link S as high as the draft-iron or coupling to which it is attached will allow said coupling-link to rise.

What I claim, and desire to secure by Letters Patent of the United States, is—

1. The combination, in a car-coupling device, of a hinged swinging device or coupler, A, having a deflecting point or outward end, R, horizontal link-rest and handles K K, and 10 attaching-strip B, substantially as shown and described, and for the use and purpose specified.

2. The combination, in a car-coupling device, of a hinged swinging device or coupler, A, having a deflecting point or outward end, R, horizontal link-rest and handles K K, and the attaching yoke or swing C, substantially as shown and described, and for the use and purpose specified.

ALLEN W. MCKENZIE.
